Primary Examiner—Marcus A. Jackson*(74) Attorney, Agent, or Firm*—Stanley Law Group LLP(57) **CLAIM**

The ornamental design for a flashlight, as shown and described.

DESCRIPTION

FIG. 1 is a top plan view of a flashlight showing one embodiment of my new design;

FIG. 2 is a bottom plan view thereof;

FIG. 3 is a left side elevation view thereof;

FIG. 4 is a right side elevation view thereof;

FIG. 5 is a front elevation view thereof; and,

FIG. 6 is a back elevation view thereof.

The broken line showing of the flashlight is for illustrative purposes only and forms no part of the claimed design.

The present application is being submitted with formal drawings.
